UNITED STATES PATENT OFFICE.

LEONARD A. YOUNG, OF DETROIT, MICHIGAN.

UPHOLSTERY-SPRING CONSTRUCTION.

1,325,344.

Specification of Letters Patent. Patented Dec. 16, 1919.

Application filed August 30, 1919. Serial No. 320,828.

To all whom it may concern:

Be it known that I, LEONARD A. YOUNG, a citizen of the United States, residing at Detroit, in the county of Wayne and State of Michigan, have invented certain new and useful Improvements in Upholstery-Spring Constructions, of which the following is a specification.

In the construction of spring seats for vehicles and furniture, particularly those of the type wherein the cushions are removable, it is desirable to provide a base frame that possesses some rigidity together with lightness, and that affords an adequate method of securing the members of the frame and the springs employed together with members of the parts, and at the same time securely holds the depending upholstery cover or apron in place without the necessity of tacking strips or like means.

This invention relates to a spring seat structure and particularly to the base frame thereof that is so designed as to possess the rigidity desired whereby the cushion may be removed bodily from the support without permanent deformation, that is readily manufactured because it is easily assembled and that is also formed so that the apron of upholstery is quickly secured without the necessity of extraneous parts.

The invention consists in the matters hereinafter set forth, and more particularly pointed out in the appended claims.

In the drawings:

Fig. 1 is a plan view, partially broken away and in section, of a spring structure that embodies features of the invention;

Fig. 2 is a view in transverse section therethrough;

Fig. 3 is a view in detail showing one form of the base rim strip and upholstery apron attached thereto;

Fig. 4 is an enlarged view in detail of a base rim strip with an inserted edge portion of an upholstery apron indicated in dotted lines; and

Fig. 5 is an enlarged view in detail of one modification of the strip.

Referring to the drawings, a base frame is formed of a sheet metal strip folded intermediate its margins to form a hollow rib 1, the upper marginal portion 2 being reverted into overlying relation to the adjacent portion of the bead or rib 1 and the lower marginal portion 4 being likewise returned in underlying relation to the under side 5 of

the bead 1. While the parts 2 and 4 are herein indicated in spaced relation to the walls 3 and 5, they may be flattened against the same, although the spaced relation of the parts herein indicated is preferred.

The marginal portion of the member 4 is turned as indicated at 6 and, similarly, the outer portion of the part 2 is down turned as indicated at 7.

The strip 1 may be made continuous around the frame or it may be built of such conveniently sized sections as desired. Cross supporting strips or transverse members 8 have their end portions inserted in the groove formed by the bead 1 where they are secured by spot welding or suitable compressing of the strip. These cross members may be of any preferred form and suitable design and are herein shown as of U-section with the flanges disposed in horizontal position, whereby the base turns 9 of body springs 10 may be inserted therein and clenched in position by pinching the embracing flanges indicated at 11. That strip 8 which is adjacent the end portion of the frame, is so disposed that the groove of the strip cooperates with the groove of the adjacent portion 12 as holding means of the base turns of the interposed body springs. The intermediate strips 8 are arranged in pairs with their flanges turned toward each other and body springs are inserted between the flanges of each pair. In order to further stay the springs, the latter may be connected by short sections 13 of U-straps that grip intermediate turns 14 of the springs, or other stay means may be used, and clips 15 are likewise employed if desired to hold the upper coils of the body springs in place.

The usual rim frame 16 is carried by the body springs if desired. Upholstery filling 17 is placed on the springs with a customary covering 18. The depending marginal portions 19 of the covering form the usual aprons.

The lower margins of the aprons which are provided with a welt edge 20 or are merely hemmed or otherwise re-inforced, are tucked between the portions 6 and 7 of the strip and secured there by the natural interlocking which results from the relation of the spacing member 6 and 7. That is, the normal distance between the outer margin of the outer portion 7 and the adjacent part of the member 6, is less than the space between the inner portions of these flanges, and when

the welt or hemmed edge is tucked therein, the spring edges of these maintain the same in position. Or if preferred, the outer member 7 may be clenched down upon the upper 5 upholstery as by an air hammer with suitably proportioned jaws for accomplishing this purpose or by hand or the like.

In the enlarged detail of Fig. 4 a rim strip is shown having a hollow bead 20 from 10 which spring rounded flanges 21 and 22, the outer edges 23 and 24 of which overlap and permit the tucking of the fabric as indicated at 25 into position in the wider space of the body of the strip itself. The walls of the 15 flanges of this construction are arched and this increases the strength of the rib against longitudinal flexion.

In Fig. 5, the strip shown in Fig. 3 is placed in reversed position with the lower 20 rib 26 overlying the depending part of the upper rib 27, the upholstery apron margin 28 being inserted in the space between the ribs and being protected against chafing on the spring support by the position of the 25 part 26.

As a result of this invention, a spring seat is obtained that is extremely rigid, while at the same time the base frame affords ready means for connection with the springs and 30 the other parts of the structure without the necessity of clips or like holding devices and upholstery is readily applied in such a manner that a continuous, unbroken grip is maintained along its margin without the necessity of tacking or the like.

Obviously, changes in the details of construction may be had without departing from the spirit of my invention, and I do not care to limit myself to any particular 40 form or arrangement of parts.

What I claim is:

1. In upholstery spring construction, a frame having a sheet metal rim strip folded intermediate its margins into a hollow rib, 45 the marginal portions being reverted and extending beyond the body of the rib with the resultant flanges turned slightly in spaced relation.

2. In upholstery spring construction, a 50 base frame including a sheet metal rim strip folded intermediate its margins into a hollow rib opening inwardly, the marginal portions being reverted to provide flanges extending outwardly beyond the body of the 55 rib, the outer portions of the flanges being turned toward each other and slightly separated.

3. In upholstery spring construction, a 60 base, a rim in the base consisting of a sheet metal strip folded intermediate its margins into an inwardly hollow rib, the marginal portions being reverted to provide outwardly extending flanges the outer portions of which are turned toward each other, body springs

mounted on the base and upholstery cov- 65 ering on the springs, the margins of which are inserted between and held by the rim flanges.

4. In upholstery spring construction, a base frame, a rim for the frame provided 70 with an inner longitudinal groove and outwardly extending resilient inturned flanges in spaced relation, supporting members secured near their extremities in the inner groove of the rim, body springs on the supports and upholstery thereon including an 75 apron, the margins of which are held between the flanges of the rim.

5. In upholstery spring construction, a base frame, a sheet metal rim strip in the 80 frame formed between its margins to provide an inner longitudinal groove with the marginal portions of the strip extending outwardly in inturned spaced relation, the frame having transverse members secured at 85 the extremities in the groove of the rim, springs on the frame, and upholstery on the springs including a covering, the margin of which is inserted between the rim flanges.

6. In upholstery spring construction, a 90 base frame rim strip formed into a hollow rib intermediate its margins providing an inner groove, the marginal portions being reverted and formed into flanges extending beyond the body of the rib and lying in in- 95 turned spaced relation, U-section transverse strips secured at their extremities in the hollow rib of the rim, body springs, the base turns of which are inserted in the grooves of the transverse and rim strips and up- 100 holstery on the springs having a depending apron which is secured along its margins by the coöoperating flanges of the rim strip.

7. In upholstery spring construction, a base frame consisting of a rim strip having 105 a longitudinal groove on its inner face and outwardly extending inturned flanges, spring supporting members spanning the frame and resting in the groove of the rim, body springs mounted on the frame, stay members con- 110 necting intermediate coils of the body springs, an upper rim frame supported by the springs and upholstery having an apron the margin of which is secured in position by the coöoperating flanges of the base frame 115 rim.

8. In upholstery spring construction, a strip forming a member of a base frame consisting of a sheet metal bar folded to form a hollow rib between the margins of the 120 strip, the substantially parallel sides of the rib being reverted to form outwardly ex- 125 tends flanges in parallel, spaced relation to the adjacent faces of the rib, the marginal portions of the flanges lying in substantially overlapped and spaced relation.

In testimony whereof I affix my signature.
LEONARD A. YOUNG.
